UNITED STATES PATENT OFFICE.

JOHN W. CAIN, OF CHICAGO, ILLINOIS.

WINDOW-WIPER.

1,203,182.

Specification of Letters Patent.

Patented Oct. 31, 1916.

Application filed October 3, 1914. Serial No. 864,813.

To all whom it may concern:

Be it known that I, JOHN W. CAIN, a citizen of the United States, and a resident of Chicago, in the county of Cook and State 5 of Illinois, have invented certain new and useful Improvements in Window-Wipers, of which the following is a specification.

This invention relates to devices for wiping water, sleet, hail, snow, and other objects from the outside of the car window in the forward ends of electric and other cars; to enable the motorman to maintain 10 an unobstructed view through said window.

The object of this invention is to obtain 15 a device of simple construction, which is effective in operation, not liable to break or get out of order, easily operated, and actuated by compressed air or other gas under pressure.

20 In the drawings accompanying and forming a part of this specification Figure 1 is a front elevation of a portion of a car front, and of this device in position thereon. Fig. 2 is a section on line 2—2 of Fig. 1, viewed 25 in the direction indicated by the arrows. Fig. 3 is an elevation, on an enlarged scale, of a portion of the tube and operative parts of the device which are positioned on the left hand side of the illustration set forth 30 in Fig. 1. Fig. 4 is a horizontal section of one of the tubes of the device, showing a portion of the frame and wiping element of the device in top plan view, on line 4—4 of Fig. 3, viewed in the direction indicated 35 by the arrows. Figs. 5 and 6 are, respectively, front and rear views of an element of the base of the wiping frame of the device. Fig. 7 is a horizontal section on line 7—7 of Fig. 8, viewed in the direction indicated by the arrows; and Fig. 8 is an elevation 40 of a guide and the upper end of a piston stem, forming elements of the device. Fig. 9 is a front elevation of a track shifting element which is positioned at the lower end of 45 the track of the device. Fig. 10 is a side elevation of the parts which are illustrated in Fig. 9. Fig. 11 is a front elevation of a modification of the track shifting element of the device, and of a portion of the tube 50 on which the same is mounted. Fig. 12 is a side elevation of the modification which is illustrated in Fig. 11.

A reference character applied to designate a given part indicates said part throughout 5 the several figures of the drawing, wherever the same appears.

A is a window sash, and *a* is the glass in sash A.

B is a portion of a front of a car.

C, C, are tubes or cylinders.

60

C¹ is a head in cylinder C.

D is a piston in cylinder C, and *d* is the stem to piston D. Head C¹ is provided with a central aperture through which stem *d* extends, and moves when piston D is moved 65 longitudinally in said cylinder C.

E, E, are tubes or cylinders which are in axial alinement with tubes or cylinders C; and said cylinders C and E are illustrated as joined together. Tubes or cylinders C 70 and E are rigidly attached to the front of the car, as by lugs E¹.

e, are longitudinally extending slots in tubes E.

*e*¹ are tracks rigidly secured to tubes or 75 cylinders E.

*e*² is the side or face of a track, (Fig. 9) which is adjacent to the car window when the device is properly mounted on a car front, and on which face the roller (G), of 80 the wiper frame element of the device travels when said wiping element is moved upward.

*FF*¹ is a tongue or latch which is pivotally attached to the lower end of track *e*¹, by 85 means of pin or bolt *f*; and *f*¹ is a spring yieldingly holding said tongue or latch in an advanced position. Part *F*¹ of latch *FF*¹ projects into the path of said downward moving roller, and said tongue or latch is 90 retracted, that is, forced into a retracted position by said roller, against the resiliency of spring *f*¹, as the wiper frame or element is near to its extreme downward position.

H is a member of the wiper element of 95 the device and is attached to the upper end of piston stem *d*. Member H comprises the part *h* which is positioned in cylinder C and is provided with enlarged ends which fit loosely to the inside of the cylinder, web 100 *h*¹ which extends through the slot *e*, web *h*², which is illustrated as rigidly secured to web *h*¹, and the depending arm *h*³, which is illustrated as integral with web *h*².

I, I¹, are rods which are secured in 105 depending arms *h*³ of elements H, on opposite sides of the window to which the device is attached. Members H and rods I, I¹, constitute what I term the wiper frame of the device.

J is the main part of the wiper which is 110 mounted on said wiper frame, and K are

ribs which are respectively rigidly attached to part J and pivotally mounted on rod I.

5 *k* is an arm which depends from the ribs K adjacent to tubes E and on which arm the roller G is rotatably mounted.

L are springs, one end of which are attached to rod I and the other end to ribs K. The rod I is secured in said elements H so as to be non-rotatable, and the springs

10 L, attached as described, tend to hold the wiper frame in position so that wiper element M is in contact with glass a.

l is a cover to spring L, and is mounted on rod I.

5 M is the wiping element of the wiper, and is mounted on the part J.

It will be observed that a rigid frame is made by elements H and rods I, I¹, and that the wiping element M may be moved on to 10 and away from contact with glass a, by means of the pivotal attachment of abutments or ribs K to said rod I. In operating the device said frame is moved up, as indicated by broken lines in said figure, and 25 returned to its initial position, or permitted to remain in its raised position, at the option of the operator. The above named movement is obtained by moving the handle of four way cock L¹, so as to admit air, (or 30 other fluid) under pressure, to above or below the pistons D, as required to produce the desired movement of said parts.

In the downward movement of the wiper frame, when roller G comes in contact with 35 part F¹, of latch FF¹, said latch is forced to a retracted position, against the resiliency of spring f¹, and as said roller moves below said latch it is returned to its advanced position. On the upward movement of said 40 wiper frame the roller G is brought into contact with the under side of said latch, and is thereby forced on to face e² of tracks e¹, and the wiper frame is turned on rod I, against the resiliency of springs L, so that 45 the wiping element is removed from said glass a. As is illustrated in Fig. 1, the roller G is carried beyond the upper end of said track e¹ when the wiper frame is in its extreme upward position; and as said 50 roller passes beyond said track the springs L return the wiper frame to its normal position, with wiping element M in contact with glass a. As said wiper frame moves downward wiping element M remains in 55 contact with said glass and wipes it.

In Figs. 11 and 12 a modification of the roller G and latch FF¹ is illustrated. In this modification the roller is mounted on a longitudinally movable shaft, g, and is held 60 in an advanced position, to engage with track e¹, by spring S; and latch FF¹, is replaced by the rigidly secured inclined track T, which acts to force said roller and shaft

g longitudinally back, or into a retracted position, as the wiper frame moves to its 65 extreme downward position. As said roller moves below track e¹ it is moved to its advanced position by spring S, and when said wiper frame again moves upward the inclined under face t forces said roller G on to 70 face e² of track e¹, to move said wiper frame so that wiping element M is removed from glass a.

O is the inlet of the upper end of the tube C and P is the inlet of the lower end 75 of said tube.

Q are supply pipes from four way cock L¹ to inlets O, and q are like pipes to inlet P.

R is the pipe for air, or other gas under 80 pressure.

Part h of member H is by me termed a guide as it maintains the upper end of piston stem d centrally located in the tubes C and E, and also holds said base in a determined position relatively to said tubes E. 85

I claim:

1. In a window wiper, a construction comprising, in combination, tubes respectively provided with longitudinally extending slots, members in said tubes respectively provided with enlarged ends loosely fitting said tubes, webs integral with said members and extending through said slots, additional webs rigidly secured to said first named webs, said members and webs adapted to 95 form bases, said additional webs respectively provided with depending ends having apertures therein, rods rigidly secured in said apertures, a window wiper loosely mounted on one of said rods, means to yieldingly hold said wiper in a pre-determined position, means to retract it from said pre-determined position, and means to move said construction from one to the other end of said tube. 100

105 2. In a window wiper, a construction comprising in combination, tubes respectively provided with longitudinally extending slots, members in said tubes respectively provided with enlarged ends loosely fitting said tubes and with webs extending through said slots, and frames comprising end members and side members, said side members rigidly secured to said end members, and said end members rigidly attached to the 110 first named webs, and a wiper pivotally mounted on said frame, means to yieldingly hold said wiper in an advanced position, means to retract said wiper from said advanced position, and means to move said 115 construction from one to the other end of said slots.

JOHN W. CAIN.

Signed in the presence of—

CHARLES TURNER BROWN,

CHARLES B. HEBRON.
